UNITED STATES PATENT OFFICE.

JOHN P. MALLETT, OF MADISON, WISCONSIN, ASSIGNOR TO NORTHERN ELECTRICAL MANUFACTURING COMPANY, OF MADISON, WISCONSIN, A CORPORATION OF WISCONSIN.

DYNAMO-ELECTRIC MACHINE.

No. 800,382.

Specification of Letters Patent.

Patented Sept. 26, 1905.

Application filed May 10, 1901. Serial No. 59,558.

To all whom it may concern:

Be it known that I, JOHN P. MALLETT, a citizen of the United States, residing at Madison, in the county of Dane and State of Wisconsin, have invented a certain new and useful Improvement in Dynamo-Electric Machines, of which the following is a specification.

My invention relates to dynamo-electric machines, and has for its object to provide a new and improved machine of this description.

My invention is illustrated in the accompanying drawings, wherein—

Figure 1 is a view of a dynamo-electric machine embodying my invention with parts omitted. Fig. 2 is a view of the armature-face of one of the pole-pieces. Fig. 3 is a section through one of the pole-pieces.

Like letters refer to like parts throughout the several figures.

I have illustrated in the drawings a construction of dynamo-electric machine adapted either for generators or motors. In this construction the cores or pole-pieces A of the field-magnets are separated from the field-magnet frame or ring B and are attached thereto in any desired manner. Such a construction permits the pole-pieces to be made of material of a different or higher permeability than the material of the support. Such a construction has numerous advantages. If the pole-pieces are of higher permeability than the field-magnet frame and of equal cross-section, the field-magnet frame becomes saturated before the pole-pieces, and if the part of the pole-piece in contact with the frame is of the same size as the cross-sectional area of the pole, but less than that of the frame, the material of the frame at the surface of contact is worked too hard and proper results cannot be obtained. In the construction herein shown I provide the pole-pieces A with an enlarged end A', so that the face of the pole in contact with the field-magnet frame is of a greater area than the cross-section of the pole-piece. The size of this enlarged end depends, of course, upon the comparative permeability of the two substances and is preferably arranged so as to compensate for the difference in permeability, and thus prevent the overworking of the magnet-frame at the points where the poles are attached. These poles are preferably round or circular, and by this construction the part of

the pole-piece around which the coil is wound can be reduced to a minimum, thus obtaining 55 the greatest number of turns for a given length of wire. The pole-pieces are connected to the field-magnet frame in any desired manner. As herein illustrated, the inner face of the frame is turned down or otherwise finished so that it will have a smooth surface all the way around. The pole-pieces are then fastened in position—as, for example, by the bolts B'. By finishing up the entire inner face of the frame the poles may be positioned 60 as desired and the number of pole-pieces may be changed or varied in any given machine, thus permitting a standard frame to be used with a varying number of pole-pieces. I also provide an enlarged pole-face opposed to the 65 armature by providing the pole with a removable end piece or tip C. The armature end of the pole-piece is provided with the projection C', preferably circular, and having the beveled or inclined face C''. The 70 removable end piece or tip C is preferably made of material different from the pole-piece and larger, so as to compensate for the difference in permeability. This end piece, as herein shown, is split, and the parts are 75 provided with openings beveled to correspond with the beveled face C''. The two pieces are placed around the projection C' and clamped in position by means of the bolts C', the beveled faces thus insuring a good contact on 80 both of the opposed faces of the pole piece and tip, for when the bolts are tightened the wedge action brings both of these faces into 85 intimate contact. This end piece when of different material concentrates the lines of force 90 toward the center and reduces the tendency of the field to shift in response to the armature reaction. By this construction it will be seen that when the pole-pieces and the magnet-frame are made of material of different 95 permeability I am enabled to obtain a small cross-section inside of the coil and yet a sufficient area on either face to allow the proper saturation of the different opposed elements, thus obtaining a maximum efficiency for the 100 material used and the coils employed. The removable end piece or tip permits the coils to be placed in position and obviates the necessity of any separate holding devices for said coils, for when the pole-tips are placed 105 in position they hold the coils securely in

place, the beveled faces preventing any slipping or displacement thereof. When this construction is used, it will be seen that the field-coils may be removed from the machine separately by removing the entire pole-piece or by simply removing the end piece or tip.

I have illustrated a particular construction embodying my invention; but it is of course evident that the form and arrangement of the parts may be varied in many particulars without departing from the spirit of my invention, and I therefore do not limit myself to the construction shown.

I claim—

- 15 1. A dynamo-electric machine, comprising a circular magnet-frame, one or more pole-pieces separate therefrom and of material having a different magnetic permeability from the material of the frame, the face of each pole-piece in contact with the frame being of greater area than the cross-section of the pole-piece, so as to compensate for the difference in permeability between the two elements, the armature end of each pole-piece provided with 20 a projecting part of smaller area than the cross-section of the pole-piece, and a removable end piece or tip presenting angularly-disposed surfaces to engage similar surfaces on the pole proper differing in magnetic permeability from the pole-piece and through which this projecting part passes, the end piece being clamped thereto said engaging face formed by an enlarged or laterally-extended flange-like body.
- 25 2. A pole-piece for dynamo-electric machines, comprising two enlarged end pieces, having faces greater in area than the cross-section of the pole through the field-coil, one of said end pieces being removably attached 30 to the pole-piece said end pieces having angularly-disposed surfaces to engage similar surfaces on the pole proper.
- 35 3. A pole-piece for dynamo-electric machines, provided with a removable end piece or tip forming part of the armature-face of the pole-piece, said pole-piece provided with a projection which passes through the removable tip, so as to be exposed and also form part of the face of the pole-piece opposed to 40 the armature, said removable tip being of material of different magnetic permeability from the material of the pole-piece said end piece or tip having angularly-disposed surfaces to engage similar surfaces on the pole proper.
- 45 4. A pole-piece for dynamo-electric ma-

chines, provided at the end near the armature with a projection, having a smaller cross-sectional area than the pole-piece, the face connecting it with the pole-piece being beveled or inclined, a removable end piece or tip of 60 material of different magnetic permeability from the pole-piece and split into two pieces so as to surround the projection on the pole-piece, the engaging faces of the removable tip being beveled to correspond with the bevel 65 of the projection, and means for clamping said two pieces around said projection so as to bring the engaging faces into intimate contact.

5. In a dynamo-electric machine, a pole-piece having a reduced end, said reduced end being formed with an undercut clamping-surface and a multipart tip or end piece clamped about said reduced end against said undercut clamping-surface. 70

6. In a dynamo-electric machine, a pole-piece formed with a beveled or undercut clamping-surface and a multipart pole-tip or end piece clamped against said surface. 75

7. In a dynamo-electric machine, a pole-piece having a reduced end, and a multipart pole-tip or end piece clamped about said reduced end. 80

8. In combination, a pole-piece and a separate pole-tip or end piece, said tip or end piece 85 being made in separable parts, and means for clamping said parts together to thereby secure them to the pole-piece.

9. In a dynamo-electric machine, a pole-piece and a pole-tip or end piece formed in 90 parts, said parts each having a clamping-surface engaging the pole-piece, and means for forcing the parts together to clamp them to the pole-piece.

10. In a dynamo-electric machine, a pole-piece and a multipart pole-tip or end piece embracing said pole-piece, and means for clamping the parts of the tip or end piece together to lock them to the pole-piece. 95

11. In a dynamo-electric machine, a pole-tip or end piece formed in two separable parts each of which have engaging surfaces, a pole-piece and means for clamping the pole-piece between the engaging surfaces of the pole-tip or end piece. 100

JOHN P. MALLETT.
